MULTIPLE POINTER FOR PENCILS

Thaddeus L. E. Haug, Berkeley, Calif.

Application November 5, 1951, Serial No. 17,295

Term of patent 14 years

(Cl. D74—23)

To all whom it may concern:

Be it known that I, Thaddeus L. E. Haug, a citizen of the United States, residing at Berkeley, in the county of Alameda and State of California, have invented a new, original, and ornamental Design for a Multiple Pointer for Pencils, of which the following is a specification, reference being had to the accompanying drawing, forming part thereof.

Fig. 1 is a top plan view of a multiple pointer for pencils embodying my new design;

Fig. 2 is an end view thereof taken from the right of Fig. 1;

Fig. 3 is a side elevational view of the multiple pointer; and

Fig. 4 is a longitudinal cross section thereof taken on the line 4—4 of Fig. 2.

I claim:

The ornamental design for a multiple pointer for pencils, as shown.

THADDEUS L. E. HAUG.
